AUTOMATICALLY OPENING TUBULAR
WATCHCASE

Herman Schlacht, Woodhaven, N. Y.

Application June 15, 1935, Serial No. 26,737

7 Claims. (Cl. 58—88)

My invention relates to the class of watch cases described in my copending application Serial No. 721,418. As described therein, in order to expose the face of the movement both hands are required.

My present invention has for its principal object to provide a tubular construction for the case which will possess all the advantages of that type of construction but which will be provided with automatically operating means whereby axial pressure exerted on the ends of the case will cause the face of the movement to be exposed.

A further object is to provide anti-friction bearings for the actuating mechanism so that the required pressure will be minimized to the fullest extent.

My means of accomplishing the foregoing objects may be more readily understood by having reference to the accompanying drawing, which is hereunto annexed and is a part of this specification, in which—

Fig. 1 is an enlarged sectional view of a tubular watch case embodying my invention;

Fig. 2 is a section taken on the line 2—2 in Fig. 1;

Fig. 3 is a side elevation showing the case closed;

Fig. 4 is a similar view with the case opened; and

Fig. 5 is a similar view showing the face of the movement.

Similar reference numerals refer to similar parts throughout the entire description.

As shown in the drawing, the case is formed of a tubular portion 1 which has one side cut away. A cap 2 is slidably but non-rotatably mounted on one end of the tubular portion. The cap 2 is held against rotation by means of a screw 27' which is fitted to a slot 28 formed in the tubular portion 1 adjacent one end. A disc 3 is fixedly secured in the tubular portion 1. This disc 3 has a central opening in which is fixedly mounted a pin 4. Threads 5 are formed on the exterior of the pin 4, the purpose of which will be hereinafter explained. One end 6 of the pin 4 is mounted in a sleeve 20 having a socket therein. The other end 7 of the pin 4 is located in a socket formed in a plate 8 which is fixedly secured to one end 9 of a rotatable cylinder 10 which is located inside of the tubular portion 1 and has the movement 11 mounted therein, a portion of the rotatable cylinder being cut-away to expose the face of said movement. This end 7 of the pin 4 furnishes a bearing for the upper end of the cylinder 10, to hold same on its center.

The other end 12 of the movement containing cylinder 10 has a plate 13 fixedly secured thereto. This plate 13 has a central stud 14 extending outwardly therefrom. The stud is fitted to and rotates in a socket 15 formed in a central hub formed on the inside of a cap 17 which closes the end 18 of the tubular portion 1. This construction serves to hold the other end of the movement containing portion on center. The cap 17 is fixedly secured to the tubular portion 10 by means of a screw 19 or in any desired manner. The pin 4, as pointed out, is mounted inside of a cylindrical sleeve or socket member 20 which is secured in the center on the inside of the cap 2. On opposite sides of this sleeve 20 are formed recesses in which are mounted anti-friction members. As shown in the drawing ball bearings 21 are employed for this purpose. These anti-friction members 21 are located intermediate the pin 4 and the sleeve 20. These balls 20 take the place of an internal thread and greatly decrease the effort required to bring about the rotation of the movement containing tube 10. An arm 22 extends outwardly from the sleeve 20 and passes through an arcuate slot 23, formed in the disc 3, and into a socket formed in the plate 8. This socket should be close to the periphery of the plate 8 as to increase the leverage of the sleeve 20 and correspondingly decrease the effort required to rotate the cylinder 10.

A coil spring 24 is mounted between the sleeve 20 and the disc 3 and serves to hold the parts normally in the position shown in Fig. 1. It may, in some cases, be found desirable to place a small cylindrical bushing around the sleeve 20 between it and the coil spring, as clearly seen in Fig. 1 of the drawing.

The operation of the case is as follows: The user of the watch desiring to see the time exerts an axial pressure between the thumb and finger, upon the caps 2 and 17 with the result that since they are non-rotatable the sleeve 20, through the medium of the threads and balls as heretofore described will be rotated. This movement obviously will swing the arm 22 in the arcuate slot 23 and carry with it the movement containing cylinder 10 at the same time compressing spring 24. Upon releasing the pressure the spring 24 will expand and thus restore the parts to their normal position as shown in Fig. 1. Since the slot 23 extends only 180 degrees it follows that the cylinder 10 will only be rotated to the position shown in Fig. 5. Notches 25 and 26 are cut out of the edges of the cut away portion of the tubular portion 1 and receive the winding stem which carries 55

the winding crown 27. It will be apparent from the foregoing that the case can be easily opened with one hand when desired.

Having described my invention what I regard as new and desire to secure by Letters Patent is:

5 1. In a sectional tubular case for watches, a tubular portion, a cap slidably secured to one end thereof, a cap fixedly secured to the other end, a movement containing cylinder rotatably mounted in said tubular portion, said cylinder having a cut-away portion to expose the face of the movement, and mechanism in said slidable cap which engages said movement containing cylinder and said slidable cap to rotate said cylinder on movement of said cap whereby pressure exerted axially of the caps will rotate said rotatable cylinder.

10 2. In a sectional tubular case for watches, a tubular portion, a cap slidably secured to one end thereof, a cap fixedly secured to the other end, a movement containing cylinder rotatably mounted in said tubular portion, there being a cut away portion in said cylinder to expose the face of the movement, means mounted on the inside of the slidable cap which engage said rotatable cylinder 15 said means being arranged to cause rotation of said rotatable cylinder upon sliding movement of said slidable cap whereby pressure exerted axially of the caps will rotate said rotatable cylinder, and automatically operating means to return 20 said rotatable cylinder to its normal position.

25 3. In a sectional tubular casing for watches, a tubular portion, a cap slidably secured to one end thereof, there being a socket in said cap, a cap fixedly secured to the other end, a movement containing cylinder rotatably mounted in said tubular portion, said cylinder having a cut-away portion to expose the face of the movement, a disc secured in one end of said tubular portion, there being an arcuate slot in said disc, a pin 30 secured to said disc, a plate secured to one end of the rotatable cylinder, one end of said pin being mounted in said plate, the other end thereof being adapted to enter the socket in the slidable cap, threads on said pin, a cylindrical sleeve surrounding said pin threads, balls mounted intermediate said pin and sleeve which engage the threads in the pin, and an arm on the sleeve which extends through said slot in said disc, said plate having an aperture into which said arm extends whereby pressure exerted axially on the 35 caps will rotate said rotatable cylinder.

40 4. In a sectional tubular casing for watches, a tubular portion, a cap slidably secured to one end thereof, there being a socket in said cap, a cap fixedly secured to the other end, a movement containing cylinder rotatably mounted in said tubular portion, said cylinder having a cut-away portion to expose the face of the movement, a disc 45 secured in one end of said tubular portion, there being an arcuate slot in said disc, a pin secured to said disc, a plate secured to one end of the rotatable cylinder, one end of said pin being mounted in said plate, the other end thereof being adapted to enter the socket in the slidable cap, threads on 50 said pin, a cylindrical sleeve surrounding said pin threads, balls mounted intermediate said pin and sleeve which engage the threads in the pin, and an arm on the sleeve which extends through said slot in said disc, said plate having an aperture 55 into which said arm extends whereby pressure exerted axially on the caps will rotate said rotatable cylinder, and a spring to return said rotatable cylinder to its normal position.

exerted axially on the caps will rotate said rotatable cylinder, and a spring to return said parts to their normal position.

5 5. In a sectional tubular casing for watches, a tubular portion, a cap slidably secured to one end thereof, there being a socket in said cap, a cap fixedly secured to the other end, a movement containing cylinder rotatably mounted in said tubular portion, said cylinder having a cut-away portion to expose the face of the movement, a disc 10 secured in one end of said tubular portion, there being an arcuate slot in said disc, a pin secured to said disc, a plate secured to one end of the rotatable cylinder, one end of said pin being mounted in said plate, the other end thereof being adapted to enter the socket in the slidable cap, threads on said pin, a cylindrical sleeve surrounding said pin threads, balls mounted intermediate said pin and sleeve which engage the threads in the pin, an arm on the sleeve which 15 extends through said slot in said disc, said plate having an aperture into which said arm extends whereby pressure exerted axially on the caps will rotate said rotatable cylinder, an inwardly extending hub on the fixed cap having a central 20 socket therein, a plate at the other end of said rotatable cylinder, and a central pin thereon fitted to and rotatable in said socket.

6. In a sectional tubular casing for watches, a tubular portion, a cap slidably secured to one end thereof, there being a socket in said cap, a cap fixedly secured to the other end, a movement containing cylinder rotatably mounted in said tubular portion, said cylinder having a cut-away portion to expose the face of the movement, a disc 25 secured in one end of said tubular portion, there being an arcuate slot in said disc, a pin secured to said disc, a plate secured to one end of the rotatable cylinder, one end of said pin being mounted in said plate, the other end thereof being adapted to enter the socket in the slidable cap, threads on said pin, a cylindrical sleeve, means mounted therein fitted to said pin threads, and an arm on the sleeve which extends through said arcuate slot, said plate having an aperture 30 into which said arm extends whereby pressure exerted axially on the caps will rotate said rotatable cylinder.

7. In a sectional tubular casing for watches, a tubular portion, a cap slidably secured to one end thereof, there being a socket in said cap, a cap fixedly secured to the other end, a movement containing cylinder rotatably mounted in said tubular portion, said cylinder having a cut-away portion to expose the face of the movement, a disc 35 secured in one end of said tubular portion, there being an arcuate slot in said disc, a pin secured to said disc, a plate secured to one end of the rotatable cylinder, one end of said pin being mounted in said plate, the other end thereof being adapted to enter the socket in the slidable cap, threads on said pin, a cylindrical sleeve, means mounted therein fitted to said pin threads, an arm on the sleeve which extends through said arcuate slot, said plate having an aperture into 40 which said arm extends whereby pressure exerted axially on the caps will rotate said rotatable cylinder, and a spring to return said rotatable cylinder to its normal position.
